SHOEMAKING

John F. Hardy, Beverly, Mass., assignor to United
Shoe Machinery Corporation, Borough of
Flemington, N. J., a corporation of New Jersey

Application November 3, 1939, Serial No. 302,740

4 Claims. (Cl. 12—142)

This invention relates to shoemaking and more particularly to improvements in methods of bottoming shoes.

It is essential in the process of attaching an outsole to a shoe that the sole be located in such relation to the shoe that the former extends out the proper distances from the shoe bottom at all points. This becomes somewhat difficult, particularly at the toe end, in the manufacture of shoes having laterally slotted heels of the type exemplified in Letters Patent of the United States No. 2,121,172 granted June 21, 1938, upon the application of Fred C. Lovejoy, since to obtain the proper interlocking of the sole and heel in such shoes, the heel end of the sole must be so positioned that it extends a substantial distance into the slot.

It is, therefore, an object of the present invention to provide a method of applying a sole to a shoe having a laterally slotted heel breast such that the sole may be quickly and accurately located on the shoe. Accordingly, the invention provides a method of shoe bottoming which comprises first attaching to the shoe a heel with a laterally slotted breast, inserting the heel end of an outsole into the heel slot to position the sole at the heel end, locating the sole laterally at its forepart, and then attaching the sole to the shoe.

The invention will be better understood when considered with relation to the accompanying drawing, in which

Fig. 1 illustrates a shoe with the heel attached and ready to receive an outsole;

Fig. 2 illustrates the steps of inserting the sole into the heel slot and applying activating solvent to the sole attaching cement; and

Fig. 3 shows the shoe on a supporting pad preparatory to the application of sole attaching pressure.

In practicing my improved method, a shoe 10 is first assembled with the usual upper and insole, the former being secured in overlasted position by any usual lasting means such as the staples 11. A shank stiffener 12 is then applied and the margin of the shoe bottom is roughened to receive a coat of cement, in which condition it is ready for the bottoming operations.

The first of these operations is the attachment of a slotted heel. The heel 14 used for purposes of illustration is of the type shown in the above-mentioned Letters Patent, and has in its breast adjacent to its attaching face a curved slot 16 of sufficient width and depth to receive the heel end of a sole. It is to be noted that the slot 16

terminates inwardly of the sides of the heel so that the edge of the rearmost portion of the sole will not be visible in the finished shoe. To provide additional support for the heel, a tongue 18 extends forward slightly over the shoe bottom. The heel may be secured to the shoe in any of the customary ways, i. e., by nails, cement, screws, or a combination thereof.

The next step in the bottoming operations is 10 the locating and attaching of the sole 20. As illustrated in Fig. 2, the sole, which is cut to exact size before attaching, is shorter than the conventional outsole, extending rearwardly beyond the heel breast no further than the base 15 of the slot 16 in the heel breast. The heel end 22 of the sole is trimmed, in the manner indicated in the above-identified Letters Patent, to form a tongue 24 which will enter and completely fill the slot 16 laterally, sufficient lateral curvature being given to it, by molding or otherwise, to correspond with the slot.

The steps necessary for the particular type of cement being used will, of course, be performed at the appropriate times. If the cement is of 25 the "two-way" type a coat is applied both to the attaching side of the outsole and to the shoe bottom. This may then be allowed to dry and an activating solution applied just previous to the assembling of the sole and the shoe.

To apply the sole to the shoe, the operator 30 turns the latter bottom side up in such a position that the heel slot is easily visible to him. He then takes the previously prepared and cemented outsole 20, and inserts the tongue 24 a 35 predetermined distance into the slot 16, preferably to the full depth of the latter so that the tongue contacts the base 26 of the slot. By this means, the heel end of the sole is located in proper registration with the shoe bottom and with the heel, since the breadth of the tongue 40 is exactly the same as the length of the slot and since in cutting the heel end of the outsole to fit the slot, the tongue is positioned to obtain the proper sole extension on either side of the 45 shank of the shoe. In addition, the sole is properly positioned longitudinally of the shoe, and a proper extension is obtained at the toe end inasmuch as the length of the sole is carefully predetermined and its heel end 22 is positioned with 50 reference to a known point, namely, the heel breast.

As illustrated in Fig. 3, the shoe is then placed 55 on a sole supporting pad 28 of any type suitable to receive a shoe with an attached heel. The forepart of the sole having been positioned

laterally relative to the shoe, either manually, as illustrated, or by means of suitable gages so as to insure that the proper extension of the sole on either side of the forepart will be obtained, sole attaching pressure is applied, as for example by pressing the shoe between heel and toe pads, 30 and 32 respectively, and the sole pad 26 of a conventional cement sole attaching machine.

Having thus described my invention, what I claim as new and desire to secure by Letters Patent of the United States is:

1. That improvement in methods of bottoming a shoe which comprises attaching to the shoe a heel having in the breast thereof a lateral slot which terminates inwardly of the sides of the heel, inserting the fitted heel end of a previously cemented short sole into the heel slot with the end of said sole abutting the base of the slot to completely fill said slot and position the sole longitudinally and laterally at the heel end, locating said sole laterally at its forepart, and applying sole attaching pressure.

2. That improvement in methods of bottoming a shoe which comprises attaching to the shoe a heel having in the breast thereof a lateral slot which terminates inwardly of the sides of said heel, providing a previously cemented outsole the heel end of which is adapted to fit into and completely fill the heel slot laterally, inserting the heel end of the sole into the slot with the end of said sole abutting the base of the slot throughout the entire width of the sole, thereby

to position the sole longitudinally and laterally at the heel end, manually positioning the forepart of the sole laterally with relation to the shoe, and applying sole attaching pressure.

3. That improvement in methods of bottoming a shoe which comprises attaching to the shoe a heel having a breast with a laterally curvilinear slot which does not intersect the sides of the heel, providing an outsole cut to exact size and having a heel end which is trimmed to fit into and completely fill the heel slot laterally, applying cement to the attaching face of said outsole, inserting the heel end of the sole into the heel slot with the end of the sole against the base of said slot, thereby to position the sole longitudinally and laterally at the heel end, locating the forepart of said sole laterally, and applying sole attaching pressure.

4. That improvement in methods of bottoming a shoe which comprises attaching a heel having formed in the breast thereof a laterally extending curvilinear slot which does not intersect the sides of the heel, bending the heel end of a short outsole cut to exact size to conform to the slot, said heel end having been trimmed to fit into and completely fill said slot laterally, applying cement to the outsole, inserting the heel end a predetermined distance into the slot, thereby positioning the sole longitudinally and laterally at the heel end thereof, locating the forepart of the sole laterally, and applying sole attaching pressure.

JOHN F. HARDY.
